DESIGN FOR A CARPET-SWEeper CASING.

SPECIFICATION forming part of Design No. 18,408, dated June 26, 1888.

Application filed February 23, 1888. Serial No. 265,052. Term of patent 14 years.

To all whom it may concern:

Be it known that I, WALTER J. DREW, a citizen of the United States, residing at Grand Rapids, in the county of Kent and State of Michigan, have invented and produced a new and original Design for Carpet-Sweeper Casings, of which the following is a specification.

The object of this design is to provide a novel carpet-sweeper casing; and it consists, to essentially, in a carpet-sweeper casing comprising a top portion, bottom, side walls, end walls, and inclined or beveled panels arranged between the top portion and the side walls, and having their ends extended beyond the end walls and also beyond the ends of the top portion.

The design is illustrated by the accompanying drawing, in which the figure is a perspective view of a carpet-sweeper casing embodying the design.

In the drawing, the numeral 1 indicates the casing as a whole, which comprises a top portion, 2, bottom, side walls, 7, (here shown as

converging downwardly,) end walls, 1^a, and inclined or beveled panels 3, arranged between 25 the top portion and side walls and having their ends 4 extended beyond the end walls and also beyond the ends of the top portion. As here shown, the bottom and side walls, 7, are coextensive in length with the inclined or 30 beveled panels.

What I claim is—

The design for a carpet-sweeper casing, consisting of a top portion, 2, bottom, side walls, 7, end walls, 1^a, and the inclined or beveled 35 panels 3, arranged between the top portion and side walls, and having their ends extended beyond the end walls and also beyond the ends of the top portion, substantially as shown and described.

In testimony whereof I affix my signature in presence of two witnesses.

WALTER J. DREW.
